CURTAIN ROD

Warren B. S. Cameron, Hillsboro, R.I., assignor to
Kenney Manufacturing Company, Cranston, R.I., a
corporation of Rhode Island

Filed Jan. 6, 1960, Ser. No. 58,944

Term of patent 14 years

(Cl. D21—6)

FIG. 1 is a view in front elevation of a curtain rod embodying the design of my invention;

FIG. 2 is a bottom plan view thereof;

FIG. 3 is an enlarged end elevational view as seen from the right of FIG. 1; and

FIG. 4 is an enlarged fragmentary perspective view showing one of the end pieces in detail.

The characteristic feature of my design resides in the combination of the curtain rod disclosed of the specific end pieces which are shaped as shown, the same employing an indented border or margin which is repeated throughout the length of the rod.

I claim:

The ornamental design for a curtain rod, as shown and described.
